UNITED STATES PATENT OFFICE.

FRANK N. NUTT, OF FLINT, MICHIGAN, ASSIGNOR TO A C SPARK PLUG COMPANY, OF FLINT, MICHIGAN, A CORPORATION OF MICHIGAN.

INSTRUMENT-BOARD ASSEMBLY.

Application filed February 19, 1926. Serial No. 89,366.

The instrument board assembly which is the subject of this application combines a pleasing appearance with simplicity in a manner to adapt it for quantity production 5 for use upon motor cars. It is of the type in which the instrument board fittings, such as gauges, switches, choke rod, and the like, are first assembled upon a plate or panel which is then secured to the instrument 10 board. For cheapness and simplicity I have used stock parts, such as bolts and nuts, for securing the fittings on the panel, and also for securing the panel on the instrument board. As the bolts preferably pierce the 15 panel they present an unsightly appearance. Consequently I have made use of a cover plate which overlies the panel and conceals the fastening devices from view thus giving to the assembly an attractive appearance. 20 This cover plate is assembled with the panel on the bench at the same time that the instruments are secured in position. The cover plate may be provided with a finish in harmony or in contrast with the finish of the 25 instruments and the exposed portion of the panel thus permitting a wide range of decorative effect. The entire design is preferably such that most of the parts may be stamped out of sheet metal.

30 In the drawings:

Figure 1 is a rear elevation of my instrument board assembly.

Figure 2 is a section on line 2—2 of Figure 1.

35 Figure 3 is a front elevation of one portion of the instrument board indicating the character of the effect secured by the present construction.

Figure 4 is a section on line 4—4 of Figure 1 showing the arrangement for securing 40 the face plate to the panel.

Figure 5 is a detail view showing the parts in process of assembly.

The reference character 2 indicates an instrument board such as is provided upon automobiles of conventional construction. The instrument board is provided with an opening to receive the plate or panel 4 which is provided with a flange 6 overlying the outer face of the board around the opening. The panel is secured to the board by means of bolts 8 having their heads counter-sunk in the face of the panel, these bolts being provided with nuts 10 cooperating with clamps indicated at 12 which engage the rear face

of the instrument board and the rear face of the panel or of the flange of one of the instrument board fittings as shown at the right of Figure 2. Bolts 14, which also have their heads counter-sunk in the face of the panel, 60 are provided with nuts 16 for cooperating with clamps indicated at 18 which serve to secure the various instrument board fittings such as speedometer 20, gauges 22, and switch 24 to the panel. With the construction so far described it is apparent that the heads of the bolts 14 and 8 are exposed on the front of the instrument board. I have accordingly provided face plate 30 which overlies the panel, conceals the heads of the bolts, 65 and is apertured for the display of the fittings. This plate is flanged at its edges as indicated at 32. The flanges which surround the fittings extending into the apertures formed in the panel as clearly shown in Figure 2, thus centering the plate and holding it 70 against rattling. The plate 30 is provided with tongues 36 which are passed through openings formed in the panel 4 as shown in Figure 4 and are thereupon bent over to hold 75 the parts together.

The face plate 30 is also utilized for the mounting of fitting 40 in which choke rod 26 is slidably mounted, the other end of the rod being guided in an opening 42 provided 80 in one of the clamping plates 18.

It will be noted that the centrally located bolts 14 are each utilized for the mounting of the ends of two different clamping plates, 85 separate nuts 16 being used for each plate.

It is apparent that my construction is simple and that all of the parts with the exception of the bolts and nuts, which are of stock sizes, are formed of sheet metal stampings. The face plate and the various fittings may be 90 assembled on the panel on the bench, the completed assembly then being secured upon the instrument board. The face plate may be given any desired finish to harmonize or contrast with the finish of adjacent parts. The 95 instruments are readily accessible for repair and the whole assembly may be removed with ease.

I claim:

1. The combination of an instrument board 105 having an opening therein, a plate provided with a flange portion adapted to bear against the outer face of the instrument board around said opening, and with a portion adapted to fit in said opening, means for detachably se- 110

curing the plate in position on the board, an instrument board fitting, means for securing said fitting on said plate comprising fastening devices having portions projecting through said plate, and an ornamental face plate secured to said first named plate and adapted to conceal the fastening devices, said face plate being insertable from the front of the instrument board.

10 2. In the combination as defined in claim 1, and a fitting mounted on said face plate.

3. The combination of an instrument board having an opening therein, instrument board fittings, a plate removably secured in said opening, said plate being apertured for the display of said fittings, means for securing a plurality of fittings to said plate in position to be inspected through said apertures, said means including securing devices having por-

tions visible from the front of said plate when the plate is in position on the panel, a face plate secured to said first-named plate to conceal said fastening devices, said first-named plate being provided with slots in its outer periphery and said face plate being provided with tongues adapted to be secured in said slots for securing the face plate on the first-named plate.

4. The combination of an instrument board having an opening therein, a panel adapted to fit said opening, instruments mounted on the panel, and an ornamental cover plate secured to the outer face of the panel, said cover plate being insertable in position from the front of the instrument board and having apertures for the display of the instruments.

In testimony whereof I affix my signature.

FRANK N. NUTT.
